DESIGN FOR A FOUNDRY SPRAY GUN OR THE LIKE

John W. Baur, Chicago, Ill., assignor to Binks
Manufacturing Company, Chicago, Ill., a cor-
poration of Delaware

Application January 22, 1945, Serial No. 117,525

Term of patent 14 years

(Cl. D62—2)

To all whom it may concern:

Be it known that I, John W. Baur, a citizen of the United States, and residing at Chicago, county of Cook, and State of Illinois, have invented a new, original and ornamental Design for a Foundry Spray Gun or the like, of which the following is a specification, reference being made to the accompanying drawing, forming a part thereof.

Fig. 1 is a side view in elevation of the foundry spray gun or the like showing my new design;

Fig. 2 is a top plan view thereof;
Fig. 3 is a front end view of the same;
Fig. 4 is a rear end view of the same; and
Fig. 5 is a bottom plan view of the same.

I claim:

The ornamental design for a foundry spray gun or the like, as shown.

JOHN W. BAUR.
